UNITED STATES PATENT OFFICE.

JOHN J. COUGHLIN, OF CHICAGO, ILLINOIS.

RAILWAY TERMINAL STATION.

1,376,407.

Specification of Letters Patent.

Patented May 3, 1921.

Application filed January 23, 1919. Serial No. 272,792.

To all whom it may concern:

Be it known that I, JOHN J. COUGHLIN, a citizen of the United States, residing at Chicago, in the county of Cook and State 5 of Illinois, have invented a new and useful Improvement in Railway Terminal Stations, of which the following is a specification.

My invention relates to railway terminal 10 stations generally and especially to stations in metropolitan or congested cities where it is desirable to have a large number of tracks with adjacent platforms arranged close together and under one roof, and the objects 15 of my improvements are, first, to economize in space; second, to so arrange the train tracks with their platforms in such manner that all the trains are equally accessible from the main public waiting room and 20 ticket offices; third, to arrange train tracks on the ground level, below the ground level and above the ground level; fourth, to so arrange the necessary incoming switch tracks that an incoming train can be 25 switched to enter any desirable track in the station be it on the highest level or the lowest level; fifth, to make a simple, cheap and practical construction and other features to become apparent from the description 30 to follow.

Considerable difficulty has been encountered in an attempt to provide a railway terminal station to accommodate the great number of trains arriving and departing 35 from metropolitan centers; generally the tracks have been arranged on one level which required a very large area of surface and necessitated the patrons to travel a long distance to reach the remote tracks from the 40 main waiting room and ticket office; the station tracks required such a large area that it became a financial burden to purchase the necessary property, furthermore the complicated network of necessary 45 switches all on the same level caused a delay in the moving of trains. All these objectionable features are eliminated by the use of my invention, which to describe so that others versed in the art to which it per- 50 tains can make and use the same, I have illustrated on the accompanying two sheets of drawings forming a part of this specification and in which—

Figure 1, is a front elevation of a railway terminal station embodying my inven- 55

tion; Fig. 2, is a similar view partly in cross section showing the train tracks on three different levels; Fig. 3, is a longitudinal sectional view of the same; Fig. 4, is a plan section of the same showing the train tracks 60 on one level with their adjacent platforms; Fig. 5, is a plan view of the converging train tracks and switches as they appear on the level above the ground level; Fig. 6, is a plan view of the converging train tracks 65 and switches as they appear on the ground level partly broken away; Fig. 7, is a diagrammatic view showing the tracks on the three levels in side elevation partly broken away and Fig. 8, is a cross sectional view 70 taken on line A—A of Fig. 6.

Similar reference characters refer to similar parts throughout the several views.

The front end of the station building is shown as containing the usual waiting room 75 9, with floors 10 above for offices, etc. The train shed 11 extends back from the main building and contains the tracks 12 and platforms 13 on the ground floor, the tracks 14 and platforms 15 on the floor above the 80 ground floor and the tracks 16 and platforms 17 on the floor below the ground floor. For convenience I have shown twelve train tracks on each of the three floors or levels and it will be understood that the 85 number of tracks arranged on each floor may be as many as desired to accommodate the traffic. The tracks 12 on the ground floor, as seen in Fig. 6, converge into the four tracks 18; the tracks 14 on the level 90 below the ground floor converge into the four tracks 19 as seen in Figs. 5 and 6, and the tracks 16 on the level below the ground floor converge into the four tracks 20 as seen in Fig. 6. The converging plan of the 95 tracks on said level is preferably identical with the plan of the tracks 14 shown in Fig. 5, but of course the tracks 20 must be located to one side of the tracks 19 outside the train shed to be on the same level there- 100 with. As viewed in the right hand half of Fig. 6, the tracks 18, 19 and 20 are on the same level, and as clearly shown in the said Fig. 6 the tracks 19 and 20 finally converge into tracks 18, at 21 where I have shown 105 four tracks as composing the main line entering the station. The number of tracks composing the main line entering the station may be as many as desired.

Having thus fully described my invention 110

what I claim as new and desire to secure by Letters Patent of the United States is:—

1. In a railway terminal station, a plurality of tracks arranged in three groups, 5 one in advance of the other, the tracks of the outer group being on the same level, the tracks of the central group being arranged some on the same level and some on an upward incline and some on a downward 10 incline and the tracks of the end group being arranged on three levels one above another substantially as shown and described.
2. In a railway terminal station, a plurality of tracks arranged in three groups, 15 one in advance of the other, the tracks of the outer group all being on the same level, the tracks of the central group being arranged in a central section and two side sections, the tracks of said central section 20 being on the same level, one half of the tracks of each side section being arranged on an upward incline and one half of the same being on a downward incline, and the tracks of the end group being arranged on 25 three levels one above another substantially as shown and described.
3. In a railway terminal station, a plurality of train tracks with suitable platforms arranged on three different levels one 30 above another, the tracks on each level arranged in four groups with a single track

connecting with each group, the four tracks connecting with the four groups on the middle level arranged substantially centrally of all the tracks of all three levels, 35 two tracks on either side of said four tracks leading to the tracks on the level below the middle level and two tracks on either side of said first named four tracks leading to the tracks on the level above the middle 40 level.

4. In a railway terminal station, a plurality of train tracks with suitable platforms arranged on a plurality of levels, the 45 tracks and the platforms on the different levels being arranged in the same vertical planes one above the other and suitable switches and inclined tracks connecting the same to the main line tracks leading into the station so arranged that a train from 50 any of the main line tracks may be diverted in its course to enter upon any desired track on any level in the station.

Having thus described and claimed my invention, in testimony whereof I sign my 55 name to this specification in presence of subscribing witnesses at Chicago, Ill.

JOHN J. COUGHLIN,
